D 20359

D 20359

UNITED STATES PATENT OFFICE.

CHARLES F. WALTHER, OF BUFFALO, NEW YORK, ASSIGNOR TO SHERMAN S. JEWETT & CO., OF SAME PLACE.

DESIGN FOR A RANGE.

SPECIFICATION forming part of Design No. 20,359, dated December 2, 1890.

Application filed July 14, 1890. Serial No. 358,746. Term of patent 14 years.

To all whom it may concern:

Be it known that I, CHARLES F. WALTHER, a citizen of the United States, residing at Buffalo, in the county of Erie and State of New York, have invented a certain new and useful Design for Ranges, of which the following is a specification.

This design is for a cooking-range; and its leading features consist of the novel ornamentation of the range as a whole, and also in the novel ornamentation of the segregable parts thereof, as will be hereinafter described, and as is illustrated in the accompanying photographs, which show, in—

15 Figure 1, a front view of the range, and in Fig. 2 a side view.

In each of the views the same reference character indicates the same part.

The characteristic features of this design 20 are the novel ornamentations which are given to the range as a whole and to the various accessory segregable parts thereof, such as the doors, the high shelf, the reservoir-supports, the draft-flue, &c.

25 The front of the body portion of the range has a pleasing effect, in that the doors A and B and the exposed end of the ash-box C are each provided with a framing 1, 2, and 3, respectively, which framings inclose panels, the 30 framings being lighter in color than the panels.

Upon the panel of the upper oven-door A there appears a design of heavy scroll-work 4, which resembles somewhat two letters S laid across and at right angles to each other.

35 The hinges of the door A have scroll appendages 5 extending upward at either side of the framing 1 of the door. Above the central portion of the warming-oven door B is the flue-door 6, which is provided with an oblong 40 frame-like design. The knob or handle of this door and also the knob or handle of the slide-damper below the grate are of ornamental rosette design 27.

The front of the range is further ornamented, in that the draft-openings 21 and 45 22, arranged, respectively, above and below the fire-chamber, are oblong in shape, with their greatest dimensions arranged vertically.

These openings are surrounded in each case 50 by a raised bead or rib, as is also the slot

through which the handle of each slide-damper extends, and which is arranged across the middle of the central one of each series of openings, said bead or rib intersecting the bead or rib around the central draft-opening. 55

The body of the range has an ornamental molding at the bottom, which consists of the bowed skirting 7, the nearly-vertical flange 8, which rests upon the floor, and the narrow substantially-horizontal portion 9 between them, this last portion giving to the molding the appearance of being beaded. Surrounding the damper in the pipe below the high shelf D is an ornamental design 10. The damper is circular in outline, and the openings into the pipe together form a cross, at the center of which is a rosette. Surrounding the damper is a circular rope-like design, from which radiate a number of rays, forming a star-like figure. The brackets which 60 support the high shelf are of scroll-work. Each consists of a main coiled portion or scroll 11, of S shape, tapering toward either end from about its central portion, where it is twisted, as at 12. In the center of the lower 65 loop or coil of the scroll 11 is a star-shaped ornament 13. The various parts of the scroll 11 are connected with each other and with the range by scroll-work 14, which, while strengthening the brackets, gives also a light 70 and pleasing effect thereto. The railing which surrounds the high shelf has at intervals twisted portions 15, and the standards or posts 16, supporting the railing, are also twisted and extended above the railing, where 75 they are provided with the star-shaped ornaments 17.

The design for the brackets which support the water-reservoir E is in general effect similar to that of the high-shelf brackets—that is 80 to say, it has a main scroll portion 18, with supplemental scroll-work, as 19, and a centrally-arranged star ornament 20.

Each bracket 29 for the towel-bar H extends from the side of the range with an under curve or bow, the outer end of the bracket 85 being looped over and extended so as to rest upon the bracket about midway of its length. Below the bracket and near the end where it joins the range is a loop 30, which gives to 90

the bracket as a whole a more graceful design.

What I claim is—

1. In a design for a range, the design for the oven-door, substantially as shown and described.
2. In a design for a range, the design for the flue-door, substantially as shown and described.
3. In a design for a range, the design for the warming-oven door, substantially as shown and described.
4. In a design for a range, the flue-front consisting of the ornamental design surrounding the damper-opening below the high shelf, substantially as shown and described.

5. In a design for a range, the design for the high shelf and its supporting brackets, substantially as shown and described.

6. In a design for a range, the design for the brackets for the water-reservoir, substantially as shown and described.

7. The design for the range, substantially as shown and described.

In testimony whereof I affix my signature in presence of two witnesses.

CHARLES F. WALTHER.

Witnesses:

HORATIO C. OLVER,
J. CLARENCE DOWNER.
